[57]

ABSTRACT

Washing compositions useful in automatic washing machines comprising conventional detergent compounds and additives and a suds suppressing piperazine derivative wherein the alkyl groups have 9-21 carbon atoms.

8 Claims, No Drawings

WASHING COMPOSITION CONTAINING SUDS SUPPRESSING AGENTS

BACKGROUND OF THE INVENTION

This invention relates to washing compositions containing piperazine derivatives as foam controlling or suds suppressing agents. Washing compositions which produce excessive suds are undesirable for use in modern drum-type washing machines. Desirably, washing compositions for use in automatic washing machines are those which initially exhibit a relatively good suds formation in the washing liquor at a low temperature (up to about 50° C-60° C) but tend to become low in suds during subsequent transition toward higher washing temperatures. Excessive sudsing or foaming is desirably avoided to prevent overflow of suds out of the washing machine.

Suds suppressing additives are added to washing compositions which are effective predominantly at temperatures higher than 60° C. Thus, this is the case with strongly foaming or sudsing anionic washing compositions of the sulfate and/or sulfonate types, or in the case of the salts of the carboxylated alkyl polyglycol ethers of the general formula, $R-(OCH_2CH_2)_n-O[CH_2]_m-COOH$, wherein R is C_8H_{17} to $C_{20}H_{41}$, n is 0 to 20, and m is 1 to 4.

A number of substances are known which can be added to washing compositions as foam or suds suppressors. Thus, it is conventional to use soaps of saturated fatty acids (DOS [German Unexamined Published Application] 2,015,435), nonionic highly molecular ethers, and esters of the ethylene oxide and propylene oxide condensation products of alcohols. Disadvantages of these substances are that they are not universally applicable in washing compositions and that they do not exhibit sufficient defoaming or desudsing action as in the case of dodecyl sulfonates and alkyl sulfates.

Furthermore, diurethanes are also known as foam suppressors (DOS 2,043,086). In these diurethanes, the optimum desudsing effect, at various temperature ranges, depends on the chain length. The diurethanes with chain lengths of 10-14 carbon atoms develop their optimum effect at 20°-60° C., while those with chain lengths of 18-22 carbon atoms at 60°-100° C. A disadvantage of the diurethanes is that isocyanates are necessary as the basic raw material, which, in turn, must be produced from amines or diamines. Long-chain amines, such as octylamine, laurylamine, or stearylamine, must be produced by a cumbersome process which involves reacting the corresponding chlorides with ammonia, or by the hydrogenation of the acid nitriles, and the reaction of the amines with the isocyanates requires even an additional, more expensive reaction step.

Triazine derivatives are also known (DAS [German Published Application] 1,257,338) as foam suppressors of a broader, universal application spectrum, which are independent of the chemical constitution of the washing composition. They are produced by reacting cyanuric chloride with alkyl amines, wherein again long-chain amines are used, which in the normal case must be manufactured in two stages from the corresponding alcohols via the chlorides, or from the acids via the nitriles. Furthermore, hydrogen chloride is formed during the reaction, which is bound with equimolar amounts of amine. The amine consumed for

binding the hydrogen chloride must first be regenerated from the salt before being reused. Therefore, the production of the triazine derivatives is cumbersome and expensive.

In accordance with the present invention a low sudsing washing composition containing a foam or suds suppressing agent has now been discovered which can be manufactured simply, inexpensively, and in high yields, which has an excellent foam controlling ability, and furthermore which can be used universally.

OBJECTS OF THE INVENTION

Accordingly, it is an object of this invention to provide an improved washing composition characterized by controlled foaming during use in automatic washing machines.

Another object of this invention is to provide a low sudsing washing composition containing a suds-suppressing agent comprising piperazine derivatives produced by simple, inexpensive, and conventional processes.

Upon further study of the specification and appended claims, further objects and advantages of this invention will become apparent to those skilled in the art.

SUMMARY OF THE INVENTION

Briefly the above objects and other objects are attained by the present invention by providing a washing and cleaning composition containing usual detergents and additives, and which is characterized in that it contains piperazine derivatives of the formula:

wherein R_1 and R_2 are alkyl groups of 9-21 carbon atoms, as the desudsing or defoaming agents.

The desudsing effect of the piperazine derivatives of this invention is excellent in combination with a great variety of detergents such as alkane sulfonates, olefin sulfonates, alkylbenzene-sulfonates (e.g., dodecylbenzene - sulfonate, dodecyloxy-propane sulfonate), fatty alcohol polyglycol ether sulfates, fatty alcohol polyglycol ethers, alkyl phenol polyglycol ethers, and carboxyalkylated fatty alcohol polyglycol ethers.

DETAILED DESCRIPTION OF THE INVENTION

The piperazine derivatives of the present invention are insoluble or of low solubility in water, depending on the length of the acyl residue. The desudsing or defoaming effect is only moderately strong at temperatures between 20°-40° C., but becomes stronger at 60° C., and reaches the optimum effect at 80° C. and there-

above. The washing compositions of this invention possess especially favorable properties if the chain length of the alkyl groups of the piperazine derivatives is 11-19 carbon atoms. The defoaming effect decreases with a reduced number of carbon atoms in the residue R, especially at a high temperature, and is hardly noticeable in the case of carbon atom numbers of below 7 in the residue R. The use of piperazine derivatives of more than 19 carbon atoms, i.e., up to 21 carbon atoms, in the residue R is not as suitable from an economical viewpoint. The higher fatty acids (e.g., behenic acid, lignoceric acid) required for the production of such piperazine derivatives are not as easy to produce, in contrast to lauric, myristic, palmitic, and stearic acids, which, when reacted with piperazine, result in excellent desudsing agents. The alkyl groups can also contain branches and double bonds, but piperazine derivatives of such chain configurations do not offer any particular desudsing advantages from a laundering standpoint as compared to the piperazine derivatives with straight chains.

The quantity of piperazine derivatives added to the washing compositions is 1-40% by weight, preferably 5-20% by weight, based on the detergents in the washing compositions. When adding less than 1%, practically no desudsing action can be observed; at above 40%, no increase in the desudsing action is particularly noticeable. The quantity of piperazine derivatives added to the washing compositions is 0.1 - 12% by weight, preferably 0.5 - 6% by weight, based on the total weight of the washing composition.

The washing and cleaning compositions can additionally contain the conventional additives, such as phosphates, silicates, carbonates, borates, cellulose derivatives, etc.

The piperazine derivatives of the invention can be produced in accordance with conventional methods, most simply and inexpensively by splitting off water from piperazine and fatty acids containing the desired R residue. The reaction is particularly simple if the reactants are refluxed in a water-insoluble solvent of an appropriate boiling point, wherein the water is removed from the cycle. Suitable fatty acids are straight-chain, native fatty acids, synthetic fatty acids having an even or odd number of carbon atoms, and with straight or branched chains. The advantages attainable by the desudsing agents of this invention reside particularly in that they are readily producible technically; that they deploy the optimum of their effectiveness at about 60° C. and thereabove; and that the foam level in the washing machines can be regulated by controlled dosages. As demonstrated in the subsequent example, they are superior to the conventional desudsing agents with respect to their desudsing action.

The foam or suds suppression set forth in the examples was measured in accordance with three different methods:

a. Air injection method according to Merrill and Moffett ("Oil and Soap" 21, 170 [1944]). In the Merrill and Moffett method, the foam is produced by air injection. The apparatus consists of a column having a height of 40 cm. and an inside diameter of 9 cm., equipped with a heating jacket. At the bottom, the column has an installed porous glass plate

having a diameter of 3 cm. 400 cc. of the test solution is introduced into the column. A marker in the form of a constriction of the column is provided 25 cm. above the level of the liquid. Air at an excess pressure of 20 cm. H₂O column is introduced into the test solution through the glass frit, and the time is measured within which the thus-formed foam has reached the marker. The longer the duration of this time (i.e., the lower the sudsing ability of the substance), the better is the effect of a desudsing additive. In case of an especially strong desudsing action, the foam or suds does not reach the marker at all; in this case, the attained suds level is indicated. Examples 1-6 were measured in accordance with the method of Merrill and Moffett. The values set forth therein are averages from five measurements.

b. Foam spraying method according to DAS 1,257,338. In the foam spraying method, the suds are generated by spraying the test solution. The device, utilized in a compact design, consists of a cylindrical vessel of stainless steel having a height of 75 cm. and an inside diameter of 26 cm. The liquid provided in the device is recirculated by a pump and sprayed from an annular pipe arranged at the top of the vessel, which pipe has numerous small openings directed downwardly. Upon impingement on the liquid below the pipe (falling height 50 cm.), suds are formed, the level of which is measured after specific times. The lower the suds level, the higher the defoaming or desudsing effect. Examples 7 and 8 were measured according to the foam spraying method.

c. Foam beating method according to DIN 53 902. In this method, the volume of the foam or suds is measured.

This procedure was employed in Example 9.

In the following examples references to German Hardness (°dH) of water is defined as follows: 1° German hardness = 0.357 milligram equivalents/liter of calcium ions, or = 17.8 p.p.m. of CaCO₃.

EXAMPLE 1

2 g. of a 50% by weight sodium dodecylbenzenesulfonate solution was dissolved in 1 liter of drinking water having a hardness of 12° dH. Then, varying amounts (0.1 g. and 0.4 g., respectively) of the desudsing agent (defoaming additive) were added to this solution. The foam or suds characteristic is tested in the apparatus according to Merrill and Moffett. The results are compiled in Table 1. It can be seen therefrom that the piperazine derivatives of this invention are superior to the defoaming or desudsing substances of the prior art in their desudsing effect.

EXAMPLE 2

In this example, the defoaming or desudsing effect of the piperazine derivatives of this invention is demonstrated in soft water and in hard water. For this purpose, 1 g. of dodecylbenzenesulfonate was dissolved in distilled water (0° dH) and in drinking water (12° dH), respectively, and the foam or suds is measured with and without the addition of a defoaming additive. The results are compiled in Table 2.

TABLE 1

Example	Defoaming Additive	Temperature			
		20° C.	40° C.	60° C.	80° C.
1	Without additive	272 sec.	242 sec.	205 sec.	148 sec.
	0.1 g. Dilauroylpiperazine	390 sec.	370 sec.	480 sec.	Foam level 20 cm.
	0.1 g. Trilaurylaminos-triazine for comparison	360 sec.	325 sec.	360 sec.	Foam level 20 cm.
	0.4 g. Dilauroylpiperazine	420 sec.	Foam level 10 cm.	Foam level 2-3 cm.	
	0.4 g. Trilaurylaminos-triazine for comparison	300 sec.	270 sec.	Foam level 10 cm.	
	0.1 g. Dipalmitoylpiperazine	390 sec.	310 sec.	Foam level 15 cm.	Foam level 6 cm.
	0.1 g. Distearoylpiperazine	360 sec.	300 sec.	300 sec.	Foam level 5 cm.
	0.4 g. Distearoylpiperazine	300 sec.	300 sec.	Foam level 10 cm.	Foam level 5 cm.
	0.4 g. Tristearylaminos-triazine for comparison	305 sec.	340 sec.	Foam level 1 cm.	Foam level 8 cm.
	0.1 g. Mixture (1:1) of dipalmitoyl- and distearoylpiperazine	330 sec.	310 sec.	280 sec.	480 sec.
	0.4 g. Dicaproylpiperazine for comparison	280 sec.	270 sec.	250 sec.	185 sec.

EXAMPLE 3

1.0 g. of olefin sulfonate ($C_{14}-C_{18}$) was dissolved in 1 liter of distilled water ($0^\circ dH$) or drinking water ($12^\circ dH$) and measured with and without the addition of defoaming substances, as described in Example 1. The results are compiled in Table 2.

EXAMPLE 4

2.0 g. of alkane sulfonate ($C_{14}-C_{18}$) was dissolved in 1 liter of distilled water ($0^\circ dH$) and drinking water ($12^\circ dH$), respectively, and measured as in Example 1 with or without adding distearoylpiperazine. The results are set forth in Table 2.

EXAMPLE 5

4 g. of a washing agent of the following composition was dissolved in 1 liter of water:

25	%	carboxymethylated alkyl polyethylene glycol
1	%	carboxymethylcellulose
3	%	magnesium silicate
2	%	sodium silicate
5	%	sodium carbonate
43.8	%	sodium sulfate
20	%	sodium perborate with 4 moles of water of crystallization
30	0.2	% optical brightener.

To this solution, 0.4 g. of the defoaming additive was added. The foaming behavior is tested in the apparatus according to Merrill and Moffett. The results are compiled in Table 3. It was found that, in a finished detergent formulation, the piperazine derivative of this invention has superior properties, in that it ensures a uniform foam level in the entire temperature range.

		$12^\circ dH$	300 sec.	290 sec.	Foam level 20 cm.	Foam level 18 cm.

EXAMPLE 6

1.0 g. of dodecylbenzenesulfonate, 2.0 g. of sodium tripophosphate, and 2.0 g. of sodium silicate were dissolved in 1 liter of distilled water (0° dH) or drinking water (12° dH) and measured as set forth in Example 1 with and without the addition of dilauroylpiperazine. The results are set forth in Table 3. The example

which contains 4.5 moles of ethylene oxide per mole of alcohol, was dissolved in 1 liter of water of 15° dH and tested without and with a defoaming agent in the foam spraying apparatus according to DAS 1,257,338, as in Example 7. The results are set forth in Table 4. It is apparent that distearoylpiperazine is also superior to behenic acid, which latter is known to be a defoaming agent.

shows that the substance of this invention, when further electrolytes are added, has a foam-regulating effect in the range from 20° to 80°C., by maintaining the time for reaching a certain foam level at about 300 seconds, independently of the hardness of the water.

EXAMPLE 7

15 liters of a solution containing, per liter of drinking water, hardness 15° dH, 1 g. of sodium dodecylbenzenesulfonate and respectively 0.1 g., 0.3 g., and 0.5 g. of the defoaming additive, were introduced into the foam spraying apparatus according to DAS 1,257,338. The pH of the solution is set to 9.5; the solution was recirculated by a pump at a rate of 465 liters/minute. The results are set forth in Table 4.

What is claimed is:

1. A low-sudsing washing composition comprising detergent compounds and additives, and 1-40% by weight, based on the weight of the active detergent compounds of the washing composition, of a suds-suppressing agent, said agent being a piperazine derivative of the formula:

wherein R₁ and R₂ each are alkyl groups of 9-21 carbon atoms.

2. The washing composition of claim 1 wherein said agent is present in amounts of 5-20% by weight, based on the weight of the active detergent compounds of the washing composition.

3. The washing composition of claim 1 wherein R₁ and R₂ each are alkyl groups of 11-19 carbon atoms.

4. The washing composition of claim 1 wherein the agent is distearoylpiperazine.

5. The washing composition of claim 1 wherein the agent is dilauroylpiperazine.

6. The washing composition of claim 1 wherein the agent is dipalmitoylpiperazine.

7. The washing composition of claim 1 wherein said agent is 0.1-12% by weight of the total composition.

8. The washing composition of claim 2 wherein said agent is 0.5-6% by weight of the total composition.
